ATTORNEY

UNITED STATES PATENT OFFICE.

EMMA C. PEASE, OF NANTUCKET, MASSACHUSETTS.

SPONGE.

Application filed March 29, 1923. Serial No. 628,553.

To all whom it may concern:

Be it known that I, EMMA C. PEASE, citizen of the United States of America, residing at Nantucket, in the county of Nantucket and Commonwealth of Massachusetts, have invented certain new and useful Improvements in Sponges, of which the following is such a full, clear, and exact description as will enable others versed in the art 10 to which it appertains to make and use the same.

My invention relates to sponges of the types used for bathing or other purposes, and is applicable either to the natural or 15 manufactured variety.

My invention has for its objects to provide a means insuring uniform wear throughout the exterior surface of the sponge; to render a sponge more sanitary 20 through increased area of evaporation; to make the handling and use of the sponge more convenient; to provide interior means of firmly holding the sponge when in use; to utilize for sponge manipulation the varying, and bodily adaptable, finger and hand 25 motions; to furnish a substantial foundation upon which the sponge may function minimizing the possibility of rupture; to eliminate much of the exterior wear to 30 which sponges have heretofore been subject and to provide a quick drying sponge from which the moisture holding zone or core is eliminated.

I accomplish the objects of my invention 35 as shown in the accompanying drawings which form a part of this specification and in which Figure 1 shows a cross sectional view (on line $x-x$ in Figure 2) of a sponge substance of convenient size within which is formed a cavity, shaped on either side to conform to the thumb, index and center fingers of the human hand. Figure 2 shows the open end view of the sponge shown in 40 Figure 1. Figure 3 shows the glove like member with which the cavity, shown in Figure 1, is lined and strengthened. Similar characters of reference refer to similar parts throughout the several views.

Referring again to Figure 1, A indicates 45 the sponge substance or body portion of the improved device from which the central moisture holding zone or core is removed to provide the cavity B. To remove the core from the sponge any suitable tool or machinery may be employed. For instance, in 50 forming the cavity in a natural sponge, it is

proposed in the present instance to use a sharp ring-shaped tool mounted on a handle and having a narrow cutter on each side, the openings between the cutters allowing 60 the pieces of core, after being cut, to fall out. The cutting tool is first manipulated to cut into the sponge at one end to roughly form the cavity and then subsequently maneuvered to develop the thumb and finger 65 cavities indicated respectively at C, D and E. The arrangement is such that the completed cavity practically occupies the center of the sponge and since the sponge is porous it is apparent that the cavity is open to the 70 atmosphere through the pores of the sponge. The water or moisture collected by a sponge is retained longest by the central portion or core of the sponge since the latter is less exposed to the atmosphere than the surface 75 portion of the sponge and, hence, the moisture evaporates far more slowly. However, by coring out the sponge in the manner just described, the central moisture holding zone or core is removed and an increase obtained 80 in the total area of evaporation, since evaporation will take place at the inner surface of the sponge, as represented by the wall of the cavity, as well as at the outer surface 85 of the sponge. The modifying of the natural structure of the sponge in this manner thus provides for a quicker drying of the sponge after use. The natural resiliency of the sponge is usually such that, even when saturated, it will not collapse to such an extent 90 as to practically obliterate the presence of the cavity. In addition to providing for a quicker drying of the sponge the cavity is also made use of as a means for enabling the sponge to be fastened or attached to the 95 hand by a grip or clutch from the inside of the sponge. This is accomplished by shaping the cavity to conform to the outline of the hand, as previously mentioned. Thus, external gripping of the sponge is done 100 away with and the life of the sponge prolonged by the consequent reduction in wear on its outer surface. It will be understood, also, that the particular shape of the cavity described enables the improved sponge to be 105 used on either the right or the left hand and by turning the sponge on either hand all parts of its exterior are readily used, thus insuring a uniform wear. The finger-fitting cavities insure a firm hold, eliminating 110 the possibility of the sponge slipping and making use of the same most convenient.

The presence of the cavity, it will be noted, has no effect upon the contour of the sponge, the exterior of which may be shaped to make it adaptable for any desired purpose.

5 To minimize the possibility of rupture and to furnish a substantial foundation upon which the sponge may function, the cavity of the sponge is lined and strengthened by a glove-like member B', shown in
10 Figure 3. This member is preferably made from a thin, rubberized net of any suitable open-weave meshed fabric and is inserted in and attached to the cavity of the sponge in the following manner: The rubberized net
15 is placed on a wax polished wooden hand, shaped to conform to the cavity in the sponge, then dipped into a solution of cement and inserted into the cavity, in which position it is allowed to dry, after which the
20 waxed form is withdrawn leaving the glove member in position and cemented to the sponge substance. With certain sponge substances of substantial strength the glove-like foundation is not desirable and may be
25 eliminated.

The advantages and adaptability of the human fingers and hand to the body are through the use of this invention adapted to sponge manipulation. Heretofore, in the
30 use of a sponge of this type it has been merely moved over the body of the user by a simple rubbing action, the thickness and consistency of the spongeous mass interposed between the hand and the body of
35 the user rendering the mass incapable of transmitting to the body any massaging or kneading movement of the fingers, due to the fact that when the ordinary sponge is gripped externally the central portion of the
40 spongeous mass serves to absorb the massaging movement of the fingers without corresponding application of such movement to the body. This objection is done away with in the provision of a sponge modified
45 according to the present invention since the

formation and lining of the cavity serves to reduce the thickness of, and to reinforce, the layer of spongeous material interposed between the body and the fingers of the user, with the result that the interposed layer is 50 caused to follow with a fair degree of faithfulness all massaging movement of the fingers.

The improved sponge may be made in various sizes and either small at the wrist 55 for use where a tight fit is wanted or loose where easy removal is desirable.

I do not desire to confine myself to the specific construction herein set forth as future practice of the art may require varying 60 forms and changes all well within the scope of the appended claims.

Having thus described my invention I claim as new and desire to secure by Letter's Patent of the United States of America:

65 1. A bath mit consisting of a body of spongeous material cored out to form a cavity shaped to receive the hand of the user and having an opening at one end of the body for the insertion of the hand, and an 70 open-weave meshed fabric lining secured within the cavity and serving to prevent disintegration of the body, said cavity serving to increase the area of evaporation.

75 2. A bath mit consisting of a body of spongeous material cored out to form a cavity shaped to receive the hand of the user and having an opening at one end of the body for the insertion of the hand, and a glove-like lining of open-weave meshed fabric 80 secured within the cavity and serving to prevent disintegration of the body, said cavity serving to increase the area of evaporation.

85 In testimony whereof I affix my signature in the presence of two witnesses.

EMMA C. PEASE.
